UNITED STATES PATENT OFFICE.

EMILIO POITEVIN AND FÉLIX RUISECO, OF GUATEMALA, GUATEMALA, CENTRAL AMERICA, ASSIGNEES OF ONE-THIRD TO CARLOS ZABALZA, OF GUATEMALA, GUATEMALA, CENTRAL AMERICA.

SEWING MACHINE.

Application filed May 22, 1923. Serial No. 640,785.

Our present invention relates generally to sewing machines and more particularly to the shuttles and under-thread supply thereof, our primary object being the provision for a materially increased thread supply tending toward an elimination of the frequent necessity for bobbin filling which exists at the present time and a further object is the provision of an arrangement of this nature which will be highly effective and efficient in use.

Our invention further aims to provide for an under-thread source in the form of a center feeding cop or ball, as well as a bobbin case or holder and a shuttle body, the former having means to tension the thread passing axially therethrough from the stationary ball or cop and also having means cooperating with the shuttle body to detachably support the case or holder in effective position.

By slightly enlarging the shuttle body except as to its race engaging hook, and correspondingly enlarging the bobbin case or holder as well as doing away with the usual metal space consuming bobbin, we greatly augment the under-thread supply and it is a still further object of our invention to do this in such manner as to still permit of the use of a metal bobbin in the bobbin case or holder in case this is desired.

In the accompanying drawing illustrating our present invention we have shown the same applied to the well known Singer sewing machine of the lock stitch oscillating shuttle type, but it is obvious that our invention may be adapted to various machines of other types employing either an oscillating or rotating shuttle.

In this drawing,

Figure 1 is a sectional view showing the upright shuttle race in operative position and illustrating our improvements properly associated therewith,

Figure 2 is a perspective view showing the shuttle, the thread cop or ball and the bobbin case or holder in detached relation,

Figure 3 is a perspective view showing the bobbin case or holder and a bobbin in detached relation,

Figure 4 is a detail perspective view of the shuttle removed, and

Figure 5 is a central sectional view through the thread cop or ball.

Referring now to these figures and particularly to Figure 1 we have shown certain parts of a sewing machine including an upright shuttle race 10 in which, in the type of machine to which we have shown our invention applied, the shuttle oscillates by virtue of its actuation by an oscillating shaft 11 seen in Figure 2, which is mounted below the bed 12 seen in Figure 1 and provided at one end with a bracket 13 having oppositely outstanding and curved arms 14 forming a segmental yoke adapted to lie along a portion of the periphery of the shuttle body 15 between the ends of its hook 16 which latter are engaged by the ends of the arm 14 so as to impart oscillating movements of the shaft 11 to the shuttle in operation.

According to our improvements the relation and interengagement of these parts are not varied in any way, our improvements lying wholly in the shuttle body 15, the bobbin case or holder 17 which in operation is detachably mounted within the shuttle body, and the source of thread supply which is disposed within the case or holder 17.

The shuttle body 15 has the usual chamber 18 within which the case 17 fits and in accordance with our improvements this chamber is substantially larger or in other words of greater diameter than that usually employed and has its wall provided with an internal annular groove 19 and a short axial groove 20, the latter providing for the introduction of a lug 21 outstanding at one point from the peripheral wall 22 of the bobbin case or holder 17 so that this lug can be thus introduced into the internal annular groove 19 and will form with these grooves 19 and 20 a bayonet connection serving as a lock to detachably hold the bobbin case within the shuttle body, upon partial rotation of the bobbin case or holder within the shuttle after its lug 21 is within the annular groove 19.

Figure 4 shows the shuttle complete and detached and illustrates the same provided in certain of its walls with openings 23 in order to lighten its weight, it being obvious that the relative arrangement and position of these apertures may be varied at will as occasion demands.

The bobbin case or holder 17 is substantially closed at one end as at 24, this end closure having an opening or openings 25 therein to lighten its weight and to permit

its rib 26 between the openings 25 to be utilized as a handle in rotating the bobbin case or holder into and out of the shuttle body.

- 5 We have also shown in Figures 2 and 5 in particular a thread supply in the form of a cylindrical cop or ball 27 whose ends are covered by paper disks 28 connected by lengthwise covering strips 29 along the 10 periphery of the cop or ball, the latter being thus of a form adapted to slidably interfit the bobbin case or holder 17 and being also adapted to admit of the withdrawal of the 15 thread from its center through an opening 30 centrally of one of the end covering disks 28.

To receive the thread centrally from the cop or ball 27, the bobbin case or holder 17 is provided with an opening 31 therethrough 20 near its center and beneath the free end of a tension finger 32 held by a screw 33 upon said end wall, the latter also having a slot 34 leading to the opening 31 and in communication with a slot 35 through the 25 peripheral wall of the case, through which the case may thus be threaded, the thread from the cop or ball passing directly out through the opening 31 as plainly indicated in Figure 2.

30 The above structure does not however preclude the use of a thread holding bobbin 36 of the usual type shown in Figure 3, from the periphery of which the thread feeds, inasmuch as we propose to slot the peripheral 35 wall of the case 17 partly therethrough at one point, as indicated at 37, through which the thread is passed to a feed opening 38 at the inner end of the slot 37, the thread 40 from this point passing upon the exterior of the case 17 to the tension plate 32 beneath

which it is extended so that it finally passes from the bobbin case in the same manner as does the thread when the cop or ball 27 is employed.

In so far as the use and support of a 45 bobbin 36 is concerned our invention simply provides for the personal preference of those who do not object to the more or less frequent refilling of the bobbin, but it is obvious that by providing for the use of a 50 cop or ball 27 we not only avoid all necessity for the refilling of bobbins but we are also enabled to greatly augment the possible capacity of a bobbin with its metal space consuming side walls and its cylindrical 55 core, and eliminate a number of small parts necessary in the usual construction.

We claim:

A shuttle for sewing machines having an enlarged chamber provided in the wall thereof with an annular groove and a longitudinal groove connecting with the annular groove, a bobbin case having a peripheral wall within the chamber and an outer integral end wall and open at its inner end, a 60 center feeding thread cop non-rotatable in the said bobbin case, said peripheral wall of the bobbin case having a lug movable into the grooves of the shuttle for detachably holding the bobbin case within the 65 shuttle chamber, and said peripheral wall and the end wall of the bobbin case having thread guiding slots leading to a feed opening adjacent to the axis of the outer wall of said case through which feed opening 70 the thread from the thread cop directly feeds axially of the bobbin case.

EMILIO POITEVIN.
FÉLIX RUISECO.
